UNITED STATES PATENT OFFICE.

GUSTAVE C. LORENZ, OF MILWAUKEE, WISCONSIN, ASSIGNOR TO A. J. LINDEMANN & HOVERSON COMPANY, OF MILWAUKEE, WISCONSIN, A CORPORATION OF WISCONSIN.

CONNECTION FOR LIQUID-FUEL BURNERS.

1,416,221.

Specification of Letters Patent. Patented May 16, 1922.

Application filed July 22, 1921. Serial No. 436,718.

To all whom it may concern:

Be it known that I, GUSTAVE C. LORENZ, a citizen of the United States, and a resident of the city of Milwaukee, in the county of Milwaukee, State of Wisconsin, have invented certain new and useful Improvements in Connections for Liquid-Fuel Burners, of which the following is a specification.

The improvements relate to means for connecting liquid hydrocarbon burners with the liquid fuel supply pipe, and have for their objects, among others, the provision of a strong and dependable connection which may be made and applied without unnecessary labor or expense, will meet all the requirements of use, may be quickly and easily adjusted to its proper position and to accommodate the parts which are connected thereby, and will provide at all times a secure and liquid-tight hollow connection between the said parts.

The improvements are illustrated in the accompanying drawings, in which Figure 1 is a plan of a portion of a wick trough or holder and fuel supply pipe, with a connection embodying the improvements mounted thereon and connecting them; Fig. 2 is a side elevation of the trough with the supply pipe, connection and a portion of the trough to which it is applied shown in vertical medial cross-section; Fig. 3 is an elevation of the supply pipe and connection and a fragment of the trough or holder; Fig. 4 is a detail of the ferrule or washer forming a part of the connection.

The trough or holder 1 may be of any suitable size, and, as shown, is of usual form, consisting of concentric cylinders with an annular space between them adapted to receive a wick 2, and to hold liquid fuel flowing thereinto from the bottom inlet 3 for absorption by the wick. It is also provided with inner and outer flanges 4 and 5 respectively, forming part of the burner.

The liquid fuel supply pipe 6 forms a connection between the reservoir and the burner, and may have as many burners as desired mounted thereon by means of the connections through which the said burners communicate with the oil supply.

The pipe clamp 7 is in the form of a saddle which fits the supply pipe 6 snugly, and is supported thereon, its lower extremities 7' being tapered and adapted to be turned around the pipe, so that when this is done

and the clamp is thoroughly soldered thereon a rigid and secure connection between the two is formed. A hollow nipple 8 extends upwardly from the saddle 7, and its bore communicates with a hole 6' in the top of the supply pipe 6, which may be drilled after the saddle is mounted on the pipe. The upper end of the nipple enters the tubular externally threaded lower extension 9 of the burner holding casting and is secured there-in by means of the union nut 10, threaded on the exterior of this casting and engaging the ferrule 11 slidably mounted on the nipple, in such a manner that the said ferrule is tightly clamped between the nut and the lower edge 70 of the extension 9.

This ferrule is preferably made of copper or some other relatively soft metal, is of annular form and has exterior bevels extending from its middle portion to its ends, 75 both of which are inclined at an angle of substantially 60 degrees to its horizontal axis. The lower edge 9' of the threaded tubular extension, which comes in contact with the upper bevel of the ferrule, and the inner 80 portion of the lower edge 10' of the nut 10, which comes in contact with the lower bevel, are disposed substantially at an angle of 45 degrees and form seats for the said ferrule, so that when the nut 10 is drawn up these 85 seats will wedge tightly with the bevel and also compress it to a certain extent, thereby forming a secure and liquid-tight connection, the ferrule tending to conform to the bevel of the seats and becoming tightly 90 swedged to the nipple 8. In this manner an absolutely oil-tight and secure connection is formed between the pipe clamp and the burner holder casting, at any point to which the latter may be adjusted vertically on the 95 former, and an adjustment of the wick holder and oil trough 1 so as to fix the level of oil therein at exactly the right height is provided for.

The upper portion of the burner holder 100 casting is split lengthwise so as to form a curved saddle to receive the bottom of the trough or wick holder 1, to which it is soldered, and a central bore communicating with the bore of the nipple 8 is formed in 105 the bottom of the saddle, so that a conduit from the supply pipe to the trough or holder 1 is provided.

In assembling the parts the pipe clamp 7 may be secured to the supply pipe and the 110

saddle 12 to the burner trough, in the manner described, and a conduit for liquid fuel then formed by drilling a hole through the bottom of the trough and the saddle 12 and 5 through the top of the pipe, thus insuring a clean and perfect oil passage. If on testing the device after assembling, or at any time while it is in use, the oil level is found to be too high or too low, the burner may be ad- 10 justed vertically by loosening the nut 10, moving the burner casting up or down and then tightening the nut, without breaking the connection by distributing any of the parts or interfering with other adjustments.

15 What I claim is:

1. A connection between the liquid fuel supply pipe and the burner of a liquid hydrocarbon stove, comprising a member secured to the supply pipe and having an upwardly extending tubular portion, a tubular member connected with and extending downwardly from the burner, and telescoping with the said upwardly extending portion, an annulus of relatively soft material 20 on one of said members, said annulus having beveled surfaces and adapted to act as a seal for the joint of the said telescoping members, one of the said members also having a beveled portion in contact with the 25 said annulus, the respective angles of the two beveled portions being different in degree.

2. A connection between the liquid fuel supply pipe and the burner of a liquid hydrocarbon stove, comprising a member secured to the supply pipe and having an upwardly extending tubular portion, a tubular member connected with and extending downwardly from the burner, and telescoping 30 with the said upwardly extending portion, an annulus of relatively soft material on one of said members, said annulus having beveled surfaces and adapted to act as a seal for the joint of the said telescoping 35 members, one of the said members also having a beveled portion in contact with the said annulus, the respective angles of the two beveled portions being different in degree, and a union nut threaded on the exterior 40 of one of said members, projecting beyond it and having inwardly turned annular beveled portions on the projecting part adapted to be brought in contact with other beveled surfaces of the said annulus by the rotation of the said nut and to press against the said annulus and compress it, whereby the latter is swedged and caused to bind on the 45 part on which it is positioned, and whereby all of the said parts are united and fixed in position.

3. A connection between the liquid fuel supply pipe and the burner of a liquid hydrocarbon stove, comprising a member secured to the supply pipe and having an upwardly extending tubular portion, a tubular

member connected with and extending downwardly from the burner, and telescoping with the said upwardly extending portion, an annulus of relatively soft material on one of said members, said annulus having 50 beveled surfaces and adapted to act as a seal for the joint of the said telescoping members, one of the said members also having a beveled portion in contact with the said annulus, the respective angles of the two beveled portions being different in degree, and a union nut threaded on the exterior of one of said members, projecting beyond it and having inwardly turned annular beveled portions on the projecting part adapted to be brought in contact with other beveled surfaces of the said annulus by the rotation of the said nut and to press against the said annulus and compress it, whereby the latter is swedged and caused to bind on the 55 part on which it is positioned, and whereby all of the said parts are united and fixed in position, the said portions of the nut which are brought in contact with the annulus being also beveled at a different angle.

4. A connection between the liquid fuel supply pipe and the burner of a liquid hydrocarbon stove, comprising a member secured to the supply pipe and having an upwardly extending tubular portion, a tubular member connected with and extending downwardly from the burner, and telescoping with the said upwardly extending portion, an annulus of relatively soft material 60 on the inner one of said members, of greater diameter than the internal diameter of the outer one, said annulus having beveled surfaces and adapted to act as a seal for the joint of the said telescoping members, one of the said members also having a beveled portion in contact with the said annulus, the respective beveled portions being inclined at different angles.

5. In a device of the character described, the combination of a connecting member 110 adapted to be secured to the supply pipe and another connecting member adapted to be secured to the burner, the said members having telescoping portions, a ring of softer material than the material of the said members slidably mounted on the exterior of the inner telescoping portion, and being of greater external diameter than the internal diameter of the other portion, and a cylindrical member threaded to the exterior of 115 one of said members and having a portion in contact with the said ring.

6. The method or process of forming a connection between the fuel supply pipe and the burner of a liquid hydrocarbon stove, 120 which consists in mounting a connecting member on the supply pipe and another connecting member on the burner, passing one member inside the other and then drilling a hole through the bottom of the burner and 125

the oil supply pipe through the said members.

7. A connection for a liquid hydrocarbon burner and its liquid-fuel supply pipe, comprising a saddle mounted on the top of the fuel supply pipe and having its lower portions turned around the said pipe, and soldered thereto and an upwardly extending portion of said member having an aperture therethrough communicating with the supply pipe. 20

8. In a device of the character described, the combination of a connecting member adapted to be secured to the supply pipe and another connecting member adapted to be 25

secured to the burner, the said members having telescoping portions, a ring of relatively soft material slidably mounted on the exterior of the inner telescoping portion, having a beveled extension and being of greater external diameter than the internal diameter of the other portion, and a cylindrical member threaded to the exterior of one of said members and having a portion in contact with the said ring.

Witness my hand this 12th day of July, 1921, at the city of Milwaukee, in the county of Milwaukee, State of Wisconsin.

GUSTAVE C. LORENZ.
